UNITED STATES PATENT OFFICE

140,683

DESIGN FOR A SLIDER BODY FOR SLIDE FASTENERS

Magnus C. Alveson, Duluth, Minn.

Application January 22, 1945, Serial No. 117,531

Term of patent 14 years

(Cl. D17—8)

To all whom it may concern:

Be it known that I, Magnus C. Alveson, a citizen of the United States, residing at Duluth, in the county of St. Louis and State of Minnesota, have invented a new, original, and ornamental Design for a Slider Body for Slide Fasteners, of which the following is a specification, reference being had to the accompanying drawing, forming part thereof.

Fig. 1 is a top plan view of a slider body for slide fasteners, showing my new design.

Fig. 2 is a side elevational view of Fig. 1,

Fig. 3 is a front elevational view of Fig. 1, and

Fig. 4 is a rear elevational view of Fig. 1.

I claim:

The ornamental design for a slider body for slide fasteners, substantially as shown.

MAGNUS C. ALVESON.
